(57) **CLAIM**

The ornamental design for a bottle with cap, as shown and described.

DESCRIPTION

FIG. 1 is a front perspective view of a bottle with cap showing my new design, wherein the bottle is shown independent of the cap in order to show features within not shown when combined;

FIG. 2 is an enlarged view of portion 2 shown in FIG. 1;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a sectional view taken along the lines of 9-9 from FIG. 1;

FIG. 10 is a front perspective view of the bottle with cap wherein the cap is secured within the bottle top opening;

FIG. 11 is an exploded front perspective view of the bottle with cap;

FIG. 12 is a front perspective view of the cap, shown independent of the bottle to show features visible when not combined;

FIG. 13 is a front view thereof;

FIG. 14 is a back view thereof;

FIG. 15 is a left side view thereof;

FIG. 16 is a right side view thereof;

FIG. 17 top view thereof; and,

FIG. 18 is a bottom view thereof.

The broken lines shown in the drawings are for the purpose of illustrating parts of the article as well as the designation of an enlargement view that form no part of the claimed design.
